TRIGGER CIRCUIT

John T. Potter, Sands Point, N. Y.

Application July 7, 1947; Serial No. 759,421

4 Claims. (CL. 250—27)

1

The present invention concerns trigger circuits and, in particular, pulse operated electronic trigger circuits.

The type of trigger circuit with which the present invention is concerned is one having two stable conditions and in which the change from one stable condition to the other may be brought about by means of an electrical pulse. A common type of trigger circuit comprises two electron tubes with grids and plates cross connected so that when one draws plate current it cuts off the other. Such a circuit when pulsed can be arranged so that the plate current shifts back and forth upon each pulse but it is stable with either plate drawing current. In order to operate this type of trigger circuit at higher and higher frequencies the value of the plate resistor must be successively reduced. Practical operation can be obtained up to one million operation per second or somewhat more with conventional tubes.

The present invention concerns circuits adapted to very high frequency triggering. In a preferred form of the present invention a multi-grid electronic tube is connected as an amplifier with its plate feeding a tuned circuit and a source of high frequency signals connected to a screened control grid. A cut-off bias is applied to another control grid so that normally no amplification of the high frequency signal takes place and no amplified signal voltage appears at the plate. A rectifier such as a thermionic diode or crystal rectifier is connected between plate and the biased control grid so that when a signal appears at the plate it is rectified and a resulting positive bias is applied to the control grid. To cause the circuit to trigger "on" a positive pulse is applied to the control grid. When the pulse is received by the grid the cut-off bias is momentarily cancelled causing the tube to amplify and apply a signal to the rectifier. The resulting bias from the rectifier holds the grid above cut-off and the tube continues to amplify in one stable mode even when the pulse stops. To reverse the trigger a negative pulse is applied to the grid causing the tube to cut-off again and return to its initial condition which is the second stable mode. An output pulse may be derived from the rectifier current.

One object of the present invention is to provide a method of and means for triggering electronically at very high rates.

Another object is to provide a trigger circuit

2

which is stable and which can be turned on or off in an extremely short interval of time.

Still another object is to provide a trigger circuit in which some of the limitations to very high speed triggering have been removed.

These and other objects will be apparent from the detailed description of the invention given in connection with the drawing.

In the drawing:

Fig. 1 shows one form of the present invention.

Fig. 2 shows a modified form of the present invention.

In Fig. 1 a multi-grid tube such as pentagrid tube 1 having a cathode 2, first control grid 3, screen grid 4, second control grid 5, suppressor grid 6 and plate 7 is utilized as a trigger tube. Plate 7 is connected through a tuned circuit consisting of inductance 10 tuned by capacitance 9 to a source of anode voltage 8. Screen 4 is connected to a suitable intermediate point of voltage source 8. The tuned circuit may be damped by a suitable resistance 11 in order to cause oscillations to die out rapidly when the grid is cut-off by a negative pulse. A source of high frequency

signal voltage in the form of high frequency oscillator 12 is connected to control grid 5 by means of lead 25. Control grid 3 is connected to a source of bias through resistor 23 of sufficient magnitude to normally cut-off plate current so that signal voltage from source 12 is not amplified and hence does not appear across the tuned circuit 9—10. Control grid 3 is also connected to grid resistor 21 which can support a pulse from pulse source 13 connected to grid 3 by means of capacitance 22. Grid resistor 21 is also in series with rectifier 15 connected to plate 7 through capacitance 16. The rectifier may be any suitable high frequency rectifier such as a crystal rectifier or a thermionic diode as shown consisting of plate 17 and cathode 18 the latter being heated by suitable means not shown. The rectifier circuit is completed by shunt resistor 20 connected from plate 17 to ground G and series inductance 19 connected between cathode 18 and grid 3. The function of resistor 20 is to discharge capacitance 16 when the signal is removed from plate 7 and inductance 19 is to keep high frequency signals from feeding back from plate 7 to grid 3. A utilization means 14 which may be any suitable device for utilizing pulses from the trigger circuit is connected across resistor 21 by means of lead 24.

In operation tube 1 triggers on upon receipt of a positive pulse from source 13 and off upon receipt of a negative pulse. Initially tube 1 is

55

3

biased beyond cut-off through resistor 23 and the high frequency signals from source 12 applied to grid 5 are not amplified and little or no high frequency signal appears at plate 7. When a positive pulse from source 13 is received by grid 3 the cut-off bias is overcome and the tube becomes operative. This causes it to amplify the high frequency signals from source 12 and the amplified signal appears at plate 7. This signal on plate 7 is rectified by rectifier 15 causing rectified current to flow in resistor 21 in such a direction as to oppose the cut-off bias. This rectified current voltage drop across resistor 21 serves to keep the tube conducting even after the actuating pulse is removed and hence the tube continues to amplify in a stable mode of operation. The rectified current drop in resistor 21 also forms a pulse which may be utilized by means 14. In order to shift the trigger back to its initial condition a negative pulse is applied from source 13 causing grid 3 to momentarily cut-off. When this happens tube 1 stops amplifying and hence the plate signal quickly dies out removing the source of bias through the rectifier. The original bias through resistor 23 will then hold the tube cut off in its initial condition which is one of its stable modes.

Fig. 2 shows a modified form of the present invention. The amplifier 26 may be a suitable high frequency amplifier capable of being controlled by means of a bias applied to it over lead 39 and producing an output across coil 27 tuned by capacitance 28 and damped by resistance 29. Initially amplifier 26 receives a cut-off bias from battery 43 through resistance 36 and signals from high frequency source 30 applied over leads 31 and 32 are not amplified and hence do not appear across inductance 27. When a positive pulse from pulse source 41 is applied to amplifier 26 through capacitance 40 and over lead 39 the amplifier is unblocked and it amplifies signals from source 30 providing signals in the output across inductance 27. Inductance 33 coupled to inductance 27 receives an induced voltage which is applied to rectifier 34. The resulting rectified current is applied over lead 35 across resistor 36 and serves to oppose the bias from battery 43 thereby keeping amplifier 26 in an unblocked state. Hence amplifier 26 continues to function until a negative pulse is applied from source 41 which returns the system to its initial condition. An output pulse may be taken off across resistance 36 and applied to a utilization means 42 to form a useful output.

This circuit which has been described above is capable of very high frequency triggering. Oscillator 12 may have an output frequency of 100 megacycles or more and with this high frequency excitation tube 1 may be turned on or off in a period of the order of one ten-millionth of a second or less.

4

While only two embodiments of the present invention have been shown and described, many modifications will be apparent to those skilled in the art and within the spirit and scope of the appended claims.

What is claimed is:

1. In a trigger circuit, the combination of, a thermionic amplifier including input and output means, a tuned circuit connected to said output means, a source of signals connected to said input means, means for applying cut-off bias to said amplifier, means for applying a pulse to momentarily oppose said bias to provide amplified signals in said tuned circuit, and a rectifier circuit connected between said tuned circuit and said bias means to maintain a signal opposed to said bias.
2. In a trigger circuit as set forth in claim 1, means for utilizing at least a portion of said rectified signal as an output pulse.
3. In a trigger circuit, the combination of, a thermionic amplifier including input and output means, a tuned circuit connected to said output means, a source of high frequency oscillations connected to said input means, means for applying a gain-reducing bias to said amplifier, means for applying a pulse to momentarily oppose said bias to provide amplified high frequency signals in said tuned circuit, means for rectifying at least a portion of said amplified signals coupled to said tuned circuit and said bias means to maintain a bias opposed to said gain-reducing bias, and means for deriving an output pulse from said rectifying means.
4. In a trigger circuit, the combination of, a thermionic vacuum tube including at least a control grid, a screened grid and an anode, a tuned circuit coupled to said anode, a source of high frequency signals connected to said screened grid, a source of negative bias connected to said control grid, means for applying a positive pulse to said control grid to momentarily oppose said negative bias to provide amplified high frequency signals in said tuned circuit, a rectifier coupled to said tuned circuit and said control grid for maintaining a positive bias on said control grid, and means for deriving an output pulse from said rectifier.
